UNITED STATES PATENT OFFICE.

CHARLES J. AHRENFELDT, OF NEW YORK, N. Y.

DESIGN FOR A PLATE OR SIMILAR ARTICLE.

SPECIFICATION forming part of Design No. 34,269, dated March 26, 1901.

Application filed April 12, 1900. Serial No. 12,638. Term of patent 7 years.

To all whom it may concern:

Be it known that I, CHARLES J. AHRENFELDT, a citizen of the United States, residing at the city of New York, county of New York, and State of New York, have invented and produced a new and original Design for a Plate or Similar Article, of which the following is a specification, reference being had to the accompanying drawings, forming a part thereof.

In the said drawings, Figure 1 is a plan view of a plate with my design placed thereon. Fig. 2 is a cross-section thereof.

The piece A is composed of three roses A', with rose-leaves interspersed and buds A² depending from the lower right-hand part thereof. From the lower right-hand rose a sprig bearing leaves and forget-me-nots A³ proceeds upwardly, while to the lower left-hand rose a single forget-me-not flower A⁴ is appended. Proceeding from the left side of this group on divergent lines are two curved stems A⁵ and A⁶, bearing leaves and forget-me-nots.

B consists of a pair of roses B', surrounded

by leaves and having a bud B² projecting upwardly from between them. A stem of forget-me-nots B³ extends downwardly beneath one of the roses, and a single flower B⁴ is appended to the other. From the right-hand side of the pair a curved stem B⁵, bearing leaves and forget-me-nots, proceeds upwardly.

The two pieces A and B are alternated to form a wreath or circular border, being connected by leafed stems C, while in the center the piece D is located. This piece is substantially the same as A, with the stems A⁵ and A⁶ omitted.

What I claim is—

The design for a plate or similar article substantially as herein shown and described.

Signed at the city of New York, in the county of New York and State of New York, this 14th day of March, 1900.

CHARLES J. AHRENFELDT.
